UNITED STATES PATENT OFFICE.

GEORGE W. FURTH, OF CLEVELAND, OHIO.

BALE-TIE BUCKLE.

1,100,128.

Specification of Letters Patent. Patented June 16, 1914.

Application filed March 31, 1913. Serial No. 758,075.

To all whom it may concern:

Be it known that I, GEORGE W. FURTH, a citizen of the United States, residing at Cleveland, in the county of Cuyahoga and State of Ohio, have invented a new and useful Bale-Tie Buckle, of which the following is a specification.

The device forming the subject matter of this application is a bale tie buckle, and one object of the invention is to provide a novel prong and opening construction whereby the buckle may be connected with the bale.

Another object of the invention is to provide novel means for holding one end of the binder upon the buckle, whereby the binder will give an inclination to the binder receiving wing and cause a prong which is located at one end of the wing to coöperate in a novel manner with the body portion of the buckle.

It is within the scope of the invention to improve generally, and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings:—Figure 1 shows the invention in perspective, applied to a bundle or bale, and in open position; Fig. 2 is a section showing the buckle positioned as depicted in Fig. 1; Fig. 3 is a section showing the buckle in closed or locked position; Fig. 4 is a plan of the blank from which the buckle is formed.

The buckle herein disclosed is fashioned from a strip of flat metal which is reduced in width at one end, as indicated at 1, to form a prong 2, the prong 2 being pointed as indicated at 3. In its longitudinal edges, the blank is provided with notches 4. Intermediate the notches 4 and the opposite end 5 of the blank there are formed openings 6, 7 and 8. These openings 6, 7 and 8 may be of any desired form. Ordinarily, the opening 6 is of unequal transverse dimensions, the longer dimension of the opening 6 being disposed transversely of the blank.

The opening 7 is widest intermediate its ends, and is tapered toward its ends. The opening 8 may be of any desired form. The distance from a line 9 located at the base of the prong 2 to a line 10 connecting the deepest parts of the notches 4 is equal to the distance between the line 10 and a line 11 representing the longitudinal center of the opening 6.

The blank shown in Fig. 4 and above described is bent along a line 12 passing through the opening 7, to form a body 14 and a rectangularly disposed lip 15. The opening 8 lies in the lip 15 and the opening 6 lies in the body 14. The opening 7 lies partly in the body 14 and partly in the lip 15 and extends across the angle defined by these parts. The blank is bent along the line 10 to form a binder receiving wing 16 and the prong 2 is bent along the line 9, into rectangularly disposed position with respect to the wing 16 as indicated at 17. The parts will thus be positioned as shown in Figs. 1 and 2.

One end of the binder 18 is engaged in the openings 7 and 8 and the other end of the binder 18 is engaged as shown at 19 in the notches 4, the parts then appearing as shown in Fig. 2. The wing 16 is then bent down until the prong 2 passes through the opening 6 as shown in Fig. 3, and enters the bale 20. Owing to the fact that one end of the binder 18 is held in the notches 4 as indicated at 19, the wing 16 will be given a slope as indicated at 21. As a consequence, the prong 2 will slant rearwardly beneath the body 14 toward the bend in the buckle, thereby enhancing the grip of the buckle upon the bale. Owing to the fact that the opening 6 lies entirely within the contour of the body 14 and is independent of both the lip 15 and the wing 16, the strength of the buckle is enhanced greatly. The prong 2, further, is located intermediate the longitudinal edges of the buckle, thus strengthening the structure, since one corner of the wing cannot be pulled up and bent independently of the other corner thereof.

The structure hereinbefore described is so constructed, that in operation, the buckle 105 will be firmly anchored upon the bale 20.

The particular form of blank shown in Fig. 4 of the drawing possesses many advantages. It is easy to strike out and manufacture, and there is a minimum waste of 110

material. A minimum amount of cutting takes place within the contour of the blank and, therefore, there is a minimum amount of distortion, the number of imperfect blanks being reduced accordingly. Owing to the fact that there are no narrow cuts or acute reentrant or interior angles, the die which cuts the blank will remain in perfect cutting condition for a long time. The blank contains no narrow or attenuated elements, subject to distortion and damage in the process of manufacture.

Having thus described the invention, what is claimed is:—

- 15 1. A bale tie buckle fashioned from a strip of flat metal, bent upon itself to form a body and a binder receiving wing coequal in width with the body and overhanging the body, there being opposed notches in the outer edges of the strip at the bend therein, the wing being provided at its end and intermediate its longitudinal edges with a prong, there being an opening located entirely within the contour of the body and in-
- 20

dependent of the notches, through which 25 opening the prong extends.

2. A bale tie buckle fashioned from a strip of flat metal bent upon itself to form a body and a binder receiving wing overhanging the body, the body being provided at one end 30 with a depending lip having an opening, there being opposed notches in the outer edges of the strip at the bend therein, the wing being provided at its end and intermediate its longitudinal edges with a prong, 35 there being an opening in the body, the prong being extended through the opening, and the wing being broadened to the rear of the prong to afford an enlarged driving surface.

In testimony that I claim the foregoing as my own, I have hereto affixed my signature in the presence of two witnesses.

GEORGE W. FURTH.
